INVENTOR.

J.B. Maples,

BY

Geo. P. Kimmel.

ATTORNEY.

UNITED STATES PATENT OFFICE

JACK B. MAPLES, OF MIDDLESBORO, KENTUCKY

SIGNAL

Application filed December 5, 1928. Serial No. 323,944.

This invention relates to signals, more particularly to a changeable warning signal to be used for the protection of section crews and construction gangs on railroads, rail-
5 ways or public highways, and has for its ob-
ject to provide, in a manner as hereinafter
set forth, a signal for positioning at a point
with respect to a railroad or highway to
warn enginemen and others to slow down
10 for the reason that the track or highway from
such point is under repairs.

As is well known in connection with rail-
road track repairs, it is the custom for sec-
tion foremen to place a sign board along the
15 track to warn enginemen and others to slow
down as the track from the sign board is
under repairs. The particular part of the
track under repair might be several hundred
feet. The sign is left standing even though
20 the track might have been finished within
an hour or two from the time the repairs
began, and as the section men are working
on the right of way there is no occasion for
the sign standing, and when standing under
25 the foregoing conditions unnecessarily causes
trains to slow down, resulting in a loss of
time and fuel and other unnecessary ex-
penses. The foregoing disadvantages are
overcome by a signal in accordance with this
30 invention and even though it be standing, it
will indicate to the trainmen and others that
they have the right of way, as the track is
clear because the construction has been fin-
ished or temporarily abandoned, and by such
35 indication it overcomes loss of time or waste
of material and in addition effects a saving
in section men's labor.

Further objects of the invention are to
40 provide, in a manner as hereinafter set forth,
a signal for the purpose referred to which
is simple in its construction and arrangement,
strong, durable, thoroughly efficient in its
use, interchangeable, conveniently attached
45 in signalling position, readily assembled and
comparatively inexpensive to manufacture.

With the foregoing and other objects in
view the invention consists of the novel con-
struction, combination and arrangement of
parts as hereinafter more specifically de-
50 scribed, and illustrated in the accompanying

drawings, wherein is shown an embodiment
of the invention, but it is to be understood
that changes, variations and modifications
can be resorted to which fall within the scope
of the claim hereunto appended. 55

In the drawings wherein like refer-
ence characters denote corresponding parts
throughout the several views:—

Figure 1 is a front elevation of a signal
in accordance with this invention. 60

Figure 2 is a fragmentary view in rear
elevation.

Figure 3 is a section on line 3—3 of Fig-
ure 1.

Figure 4 is a section on line 4—4 of Fig-
ure 1. 65

A warning signal, in accordance with this
invention includes means for indicating to
an engineer the beginning and ending of the
working period for a repair gang on a track 70
section, whereby when the signal comes with-
in the vision of the engineer such means will
indicate whether the engine should be slowed
down or if the track is clear for right of way.
If the signal is noted between the beginning 75
and ending of the working period of the re-
pair gang the engineer will then know he is
to slow down, but if noted before the begin-
ning or after the ending of such working
period the engineer will then know that the 80
track is clear and he has right of way.

Referring to the drawings in detail a sig-
nal, in accordance with this invention includes
a standard 1 of the desired height for anchor-
ing the device at the desired point with re-
spect to a railroad track, railway or highway. 85
Secured against the rear of and extending
to a point below the top of the standard 1
is a rectangular plate 2 of suitable width
and length. The upper portion 3 of the stand-
ard 1 is projected a substantial distance above
90 the top of plate and is adapted to be impacted
upon by a striking element for driving the
standard 1 into the ground. Spaced hold-
fast devices 4 are provided for fixedly secur-
ing the lower portion of the plate 2 to the
95 standard 1.

Arranged at the rear and above the bottom
edge of plate 2 is a back plate 5 of rectangu-
lar contour and which has its top and ends 100

flush with the top and side edges of plate 1. The plate 5 at its lower end is formed with a forwardly extending, right angularly disposed flange 6 which abuts against the inner face of plate 2 approximately at the longitudinal median of the latter. The flange 6 provides means for spacing the lower portion of plate 5 from plate 2 and provides in connection with a pair of spacing members 7, 8 and a partition bar 9 a pair of compartments 10, 11 which are closed at their lower ends by the flange 6 and which have their upper ends open. The sides of the compartments 10, 11 are formed by the spacing bars or members 7, 8 and partition bar 9. The partition bar 9 is arranged parallel to the standard 1 and disposed at the vertical center of the plates 2 and 5.

The spacing member or bar 7 is secured to plates 2 and 5, by spaced holdfast devices 12. The spacing member or bar 8 is secured to the plates 2 and 5 by spaced holdfast devices 13, and the partition bar 9, plate 5, upper portion of plate 2 and standard 1 are secured together by spaced holdfast devices 14.

The upper portion of plate 2 is formed with a pair of spaced, enlarged openings 15, 16 preferably square in contour and the former provides an open front for compartment 10 and the latter an open front for the compartment 11.

Removably mounted in the compartment 10 is a carrier 17 for indicia 18 and removably mounted within the compartment 11 is a carrier 19 for indicating indicia 20. The carriers 17, 19 are in the form of flat plates of greater height and width than either of the openings 15, 16. The indicia on the carrier 17 is to indicate the time of the beginning of the working period of a repair gang and the indicia on the carrier 19 to indicate the time of the end of the working period of the repair gang, that is to say as illustrated the carrier 17 is provided with a digit seven and the carrier 19 with a digit two and the digits coact to indicate that the working period of the repair gang starts at 7 a. m., and closes at 2 p. m., therefore if the signal is standing and is viewed by the engineer before 7 a. m., he will know then that the repair gang is not at work and has the right of way, or if the signal is upstanding and viewed after 2 p. m., the engineer will know that the repair gang has ceased its work and that the track is clear. If the signal is upstanding and is viewed by the engineer between the hours of 7 a. m., and 2 p. m., the engineer will know that the gang is at work and that the train should be slowed down. The signal is positioned the desired distance forwardly with respect to the portion of the track which is being repaired.

The indicia shown is illustrated merely by way of example, as same can indicate a dif-

ferent time for the start and a different time for the ending of the working period for the repair gang.

The compartments provide means whereby the carriers with different indicia can be selected and mounted therein after the removal of those carriers which have been arranged in the compartments. The compartments 10 and 11 can be of any suitable width.

It is thought the many advantages of a signal, in accordance with this invention and for the purpose set forth can be readily understood, and although the preferred embodiment of the invention is as illustrated and described, yet it is to be understood that changes in the details of construction can be had which fall within the scope of the invention as claimed.

What I claim is:

A signal comprising a vertically disposed rectangular front plate provided with a pair of opposed spaced openings between its transverse median and its upper end, a back plate opposing the rear face of the front plate and having its lower end formed with a forwardly directed flange abutting such rear face below and in proximity to said openings, a pair of outer and an inner spacer member, arranged in spaced relation and interposed between and forming in connection with said plates a pair of spaced compartments, indicia carrying means removably mounted in said compartments and having the indicia thereon exposable through said openings, means for securing said plates and outer spacer members together, a standard having a portion intermediate its ends positioned against the outer face of said front plate between said openings, and means common to said plates, intermediate spacer member and standard for rigidly connecting them together.

In testimony whereof, I affix my signature hereto.

JACK B. MAPLES.
